UNITED STATES PATENT OFFICE.

ANDREW HARTER, OF DELPHI, INDIANA.

IMPROVEMENT IN GRAIN-TALLYING MACHINES.

Specification forming part of Letters Patent No. 59,217, dated October 30, 1866.

To all whom it may concern:

Be it known that I, ANDREW HARTER, of Delphi, in the county of Carroll and State of Indiana, have invented certain new and useful Improvements in Grain-Tallying Machines; and I do hereby declare that the following is a full and complete description of the construction and operation of the same, reference being had to the accompanying drawings, making a part of this specification, in which—

Figure 1 is a plan view of the machine. Fig. 2 is a side elevation. Fig. 3 is a front-end view. Figs. 4 and 5 are sectional views.

Like letters of reference refer to like parts in the different views.

A represents the frame of the machine, which is of a suitable construction for the operating parts. B B' is a platform, arranged between the side pieces of the frame, the middle piece, B', of which extends back, is pivoted at a to the frame, as indicated by the dotted lines in Fig. 2, and to the front end is pivoted a vertical arm, C, (seen in Fig. 4,) which, at the top, comes against a ratchet-spring, J. This spring is secured to one side of the upright portion of the frame, curves down round a ratchet-wheel, D, and the end is formed into a notch that catches into the teeth of the wheel, as represented in Fig. 4, whereby the wheel is turned by the weight on the platform, as will be described.

The ratchet-wheel D is secured on a shaft, I, that has its bearings in the frame, the front end of which passes through the center of an index-plate, E, placed on the upright portion of the frame, as shown in Fig. 3.

b is a pawl attached to one side of the frame, that catches into the teeth of the ratchet-wheel D, to prevent it from turning back. Inside of the front index-plate, E, there is another index-plate, F, as seen in Fig. 5, which is secured to a sleeve, h, that is placed on the shaft I. On this sleeve there is a wheel, L, that is notched around the edge, as shown in Fig. 4, and into these notches fits the end of a spring, m, attached to the frame for holding it in place.

Around on one side of the wheel project pins i. (Seen in Fig. 5.) These pins come in contact with a spring-catch, o, (seen in Fig. 5,) that curves around and is attached to one side of the wheel D, as indicated by the dotted lines n in Fig. 4.

f is a cam secured to the frame, turned outward at the end, as seen in Fig. 5, which is for the purpose of moving out the spring-catch when it comes around against it, so that one of the pins i will strike against the catch, that will turn the wheel L, and consequently the index-plate F. When the catch o passes off the cam it will spring back, and not come in contact with the pins till the wheel D turns round again. The spring m, fitting into the notches of L, as before stated, holds the wheel stationary.

t is a pointer on the plate E, fastened on the end of the shaft I, for indicating the number on the index, the index being divided off and marked on the plate, and by means of the two index-plates from one to five hundred bushels can be tallied. A small square is cut out in the outside plate to present the number on the inner plate, that is turned or moved one number for every time that the pointer t moves once around on the plate E.

In tallying grain by this machine it can be placed near a thrasher or other machine for discharging grain, and a basket or receptacle of some kind placed on the platform B B' to receive the grain, and when one half-bushel is poured in the weight will cause the platform to descend at the front end, so that the rear end will be tipped up, causing the arm C to force up the spring J, so that the wheel D will be turned one notch. The pawl b will prevent the wheel from turning back. The elasticity of the curved spring J will cause it to spring back and catch into another tooth when the weight or grain is removed from the platform. This movement of the wheel D turns the shaft I, so as to cause the pointer to indicate a half-bushel on the index E. As another half-bushel is poured into the receptacle the wheel D is turned another notch in the same manner, and so on until the pointer t has been moved entirely round on the plate E, when twenty-five bushels will be tallied, every movement of the pointer counting one half-bushel, or one bushel, according as the machine may be constructed and arranged.

When the pointer has been turned entirely around on the plate, or the ratchet-wheel caused to make one revolution, the spring-catch o is moved out by the cam f against the pins i, so that it comes against one of them,

when the wheel L will be turned one notch, moving the plate F, so as to present a number noting what has been counted by the other plate. If the tallying has just been commenced, the number will be twenty-five, as twenty-five is counted every time the pointer moves once around on the plate E, and every movement of the plate F adds twenty-five, twenty-five being the first, fifty the next, and so on up to five hundred. Any number above what is indicated on the plate F is found by adding the number indicated on the plate E, if it is five, ten, or twenty, (more or less,) to the number presented on the index F.

What I claim as my improvement, and desire to secure by Letters Patent, is—

The combination of the platform B B', arm C, and wheels D with the wheel L, sleeve h, and index-plate E, constructed, arranged, and operating in the manner substantially as shown and described, and for the purpose set forth.

ANDREW HARTER.
